UNITED STATES PATENT OFFICE

WILLIAM POPPENDIECK, OF CARLSTADT, NEW JERSEY.

MACHINE FOR ENVELOPING A METAL CORE IN A PLASTIC BODY.

No. 850,780.

Specification of Letters Patent.

Patented April 16, 1907.

Application filed August 3, 1905. Serial No. 272,546.

To all whom it may concern:

Be it known that I, WILLIAM POPPENDIECK, a citizen of the United States of America, residing at Carlstadt, county of Bergen, State of New Jersey, have invented a certain new and useful Machine for Enveloping a Metal Core in a Plastic Body, of which the following is a specification, reference being had to the accompanying drawings, forming a part hereof.

My invention relates generally to an apparatus for covering a metal core with plastic material, so that the metal core gives strength to the plastic material.

My invention consists, essentially, in cutting into suitable lengths flat pieces of plastic material, such as celluloid, which under heat and pressure is shaped about a core of metal, uniting the plastic material and forming the same into a straight bar tapered at the ends and suitable for shaping into the form of a hair-pin or like article.

The object of my invention is the rapid and cheap manufacture by a machine substantially automatic in operation of plastic bodies with metal cores which are suitable for shaping into hair-pins and like articles; and to this end the invention consists in various details of construction to be hereinafter described, and particularly pointed out in the claims.

My invention will be better understood when described in connection with the accompanying drawings, in which similar letters of reference designate corresponding parts throughout the several views.

Figure 1 shows a vertical side view of machine with the supporting-frame removed. Fig. 2 is the front view of Fig. 1. Fig. 3 is a vertical side view showing driving mechanism, and Fig. 4 is a front view of Fig. 3. Fig. 5 shows vertical section of metal-core-feed mechanism, and Fig. 6 is front view of Fig. 5. Figs. 7, 8, 9, 10, 11, 12, 13, 14, 15, 16, 17, and 18 show details hereinafter explained.

Figs. 1 and 2 show heated cutter-plate *a*, which may be heated by a gas or similar burner, (indicated below the plate in Fig. 1,) the cutter *b*, and forming-punch *c*, that are operated by the eccentrics *A A' B*, all mounted on shaft *C*; the drum *D*, which has an intermittent motion on shaft *E* and having on its face sets of forming-jaws *d' d*.

Figs. 3 and 4 show driving mechanism, in which *G* is the driving-shaft, on which is mounted gear *H*, which, meshing with gear

I, forms an intermittent gear of the well-known Geneva stop-motion type. Gear *I* is mounted on shaft *K*, and which in turn drives pinion *J*, which is also on shaft *K*. Pinion *J* meshes with drum-gear *L*, mounted on drum-shaft *E*. By the intermittent gear *H* and *I* the drum *D* receives its intermittent motion. Figs. 3 and 4 show gear *M* mounted on shaft *G* and meshing with corresponding gear *N*, mounted on shaft *C*, on which are the eccentrics *A A' B*. *O* represents part of frame.

The cutter *b*, Figs. 1 and 2, is hollow, so as to permit the forming-punch *c* to operate within it. The inner sides of the cutter, as will readily be seen by reference to Fig. 12, act as guides or sleeves for the forming-punch *c*. The cutter *b* is fastened rigidly to the yoke-piece *u*, which at its center is connected by wrist-pin *y''* to screw-rod *w''*, which is adapted to screw into nut *v''*, which in turn screws onto screw-rod *x''*, *x''* forming a turned-buckle adjustment with eccentric *B*. By the turned buckle, composed of wrist-pin *y''*, screw-rod *w''*, and the nut *v''*, the cutter is adjustable vertically. The yoke-piece *u* acts as a slide and is housed at both ends in guides *o'*, Figs. 3 and 4.

The forming-punch *c*, Figs. 1 and 2, operating within cutter *b*, has screw-rods *w w'* swiveled at its ends by means of wrist-pins *y y'*, which, with nuts *v v'*, respectively, and screw-rods *x x'*, respectively, connect eccentrics *A A'* mounted on shaft *C* and form turnbuckle adjustments.

By the turnbuckles, composed of screw-rods *w w'*, swiveled at their ends by wrist-pins *y y'*, screw-rods *x x'*, and nuts *v v'*, the forming-punch is adjustable vertically.

The stop *T* is adjustable horizontally, so as to be moved nearer to or away from the cutter, thereby permitting of a larger or smaller piece of plastic material being cut off, as may be desired.

Figs. 5, 6, 7, and 8 show details of metal-core feed. Into hopper *Q* are placed metal cores of the desired length and diameter. At the lower end of the hopper is an opening through which the metal cores pass by gravity. Under the opening is a drum *i*, which has in it a groove *j*, running its entire length and of a size sufficient to receive one metal core at a time. About the drum *i* is a case to keep the metal core in a groove *j* during the revolution of the drum. Drum *i* is driven by means of a chain or other suitable device from shaft *C* and so timed that the drum dis-

charges the metal core held by it into the elongated end of the case when the forming-jaws d', d , holding a partly-formed tube, are beneath it, and by gravity the metal core moves to point k , where a plunger l , operated by lever m , Fig. 5, fulcrumed at point n and operated by cam o , forces the metal core into the partly-formed tube at point p , Fig. 8.

Figs. 9, 10, and 11 show details of forming-jaws d', d and their operating mechanism. Forming-jaw d' is stationary, while forming-jaw d is fastened to the slide r and by means of the set-screw h can be adjusted so that the two forming-jaws may be set nearer together or farther apart, so as to permit the forming-jaws to receive material of different diameter or to increase the pressure on the material, as may be desired. A headed pin s passes through a hole in finger e in such a manner that the head of pin s forms a stop against finger e . At one end pin s is fastened to sliding piece r , so that when finger e is moved back against the head of pin s the slide r is pulled back, which in turn pulls back jaw d , thereby opening the forming-jaws. To close forming-jaws, set-screw h is moved forward against sliding piece r , which bears jaw d , by the finger e , which is moved by lever g , which is fulcrumed on shaft f , and lever g is operated by the stationary cam F , so that at the highest point in the cam the jaw d is closed against jaw d' and is kept closed during a period that the drum D is revolving, and jaw d is opened by the stationary cam P during the remaining time that drum D is revolving. Each set of forming-jaws on drum D has similar operating mechanism attached to them and adapted to be operated in the same way, as herein particularly described.

Figs. 12, 13, 14, 15, 16, 17, 18 show the different steps of forming the plastic substance about the metal core. Fig. 12 shows a flat sheet of plastic material q lying on the cutter-plate a , that is heated by a gas-flame, Fig. 1. Fig. 13 shows the cutter b having passed through the plastic material and the part cut off forced down by the cutter b until it comes to the jaws d', d . Fig. 14 shows forming-punch c forcing the plastic material into the jaws d', d , so as to make a partly-formed tube in the shape of a U . Fig. 15 shows the metal core deposited in the partly-formed tube. Fig. 16 shows jaws d', d closed and the surplus plastic material protruding. Fig. 17 shows jaws closed and surplus plastic material removed. Fig. 18 shows the finished product of plastic material with a metal core.

The operation of the machine is as follows: With the machine put in motion the operator places on cutter-plate a a sheet of plastic material and pushes the same under the cutter b to the adjustable stop t . The cutter descends and cuts off a strip of the material and forces the strip thus cut off down toward

the forming-jaws d', d . Just as the strip comes into contact with the upper flat side of the forming-jaws, which at that point are open, the forming-punch c descends and forces the plastic material into the forming-jaws, and upon the withdrawal of punch c the plastic material is left in the forming-jaws in the form of a U , its upper flat edges resting on the jaws and holding it in proper position, as indicated. The forming-punch and the cutter withdrawing from the forming-jaws permit the operator to push the sheet of plastic material under the cutter to stop t again, and while this operation is being repeated the forming-jaws, holding the partly-formed U -shaped tube, moves a space as drum D revolves intermittently in the direction of the arrow, and empty forming-jaws come into position under the cutter and forming-punch, and the operation of cutting off a strip is repeated. While the subsequent piece of plastic material is being cut off and formed in the forming-jaws a metal core is being forced by the metal-core plunger l , Fig. 8, into the partly-formed tube at point p . There is now in the machine one partly-formed tube with a metal core in it and a partly-formed plastic tube in the form of a U . The drum now revolves another space, and as it moves lever g , passing over the cam F , forces the forming-jaws together, so as to close about the plastic material holding the metal core. The second partly-formed U -shaped tube is advanced to receive a metal core, and a third set of forming-jaws is receiving a portion of plastic material. After the forming-jaws are closed they are kept closed by cam F until the forming-jaws with a completely-formed tube that contains a metal core reaches the lowest point in the revolution of drum D , when the forming-jaws are opened by lever g passing off of cam F and into cam P , Fig. 11, and the completed product is discharged into a receptacle conveniently placed for that purpose. The first set of forming-jaws are now empty and open and ascend under the cutter and forming-punch to receive another strip of plastic material. Each successive set of forming-jaws on drum D is filled and operated the same way herein described, and the operation is repeated continuously.

I claim as my invention and desire to secure by Letters Patent—

1. In hair-pin machines, an intermittently-rotating drum, forming-jaws mounted on said drum, means to relatively move coöperating forming-jaws, a heated cutter-plate and stop coöperating with said jaws, a movable cutter and forming-punch coöperating with said cutter-plate to sever a sheet of heated plastic material and force the same within said forming-jaws, metal-core-feeding means to coöperate with said forming-jaws at another station to feed a metal core within

said material inserted in said jaws, said jaws thereafter closing to force said covering material around said core and sever the excess of said material, said jaws remaining in closed position until said material has set.

2. In hair-pin machines, an intermittently-rotating drum, series of forming-jaws on said drum, means to relatively move co-operating jaws as said drum rotates, a heated cutter-plate, means to sever a sheet of plastic material and force the same within a set of co-operating jaws and means co-operating with said jaws at another station to feed a metal core within said material, said jaws thereupon closing to force said material around said core and sever the excess of said material.

3. In hair-pin machines, an intermittently-rotating drum, series of co-operating jaws on said drum, means to relatively move said co-operating jaws, means to feed a curved sheet of plastic material between said jaws, means to feed a metal core within said material to be inclosed thereby.

25 4. In hair-pin machines, an intermittently-rotating drum, series of co-operating forming-jaws mounted on said drum, means to feed a sheet of plastic material in curved form into said jaws, means to feed a core of less length than said sheet within the same in said jaws, means to close said jaws to completely inclose said core within said material and sever the excess of said material.

5. In hair-pin machines, an intermittently-rotating drum, a series of co-operating forming-jaws on said drum, means to feed plastic material within said forming-jaws, means to feed a core within said jaws and means to close said jaws to cause said material to inclose said core.

6. In hair-pin machines, co-operating forming-jaws, automatic means to feed plastic material and a core to said forming-jaws and means to close said jaws to cause said material to inclose said core.

7. In hair-pin machines, a movable support co-operating forming-jaws on said support, means to feed plastic material within said forming-jaws, means to feed a core within said forming-jaws and means to close said jaws to cause said material to envelop said core.

8. In hair-pin machines, co-operating forming-jaws, means to feed a curved strip of plastic material within said forming-jaws, means to feed a core of less length than said strip within said strip and means to close said jaws to cause said material to completely envelop said core and to sever the excess of plastic material.

9. In hair-pin machines, co-operating forming-jaws, means to feed a strip of heated plas-

tic material in curved form within said jaws, means to feed a core within said material and automatic means to close said jaws to cause said material to engage said core and envelop an end of the same.

10. In hair-pin machines, co-operating forming means, means to feed a portion of plastic material and automatic means to feed a core within said forming means and means to operate said forming means to bring said plastic material and core into engagement and cause said material to envelop an end of said core.

11. In hair-pin machines, co-operating forming means, means to feed within said forming means a strip of plastic material in curved form to receive a core and means for operating said forming means to bring said plastic material into engagement with said core.

12. In apparatus for making hair-pins, a platen and a pair of relatively movable forming-dies thereon, normally held in separated position, in combination with a forming-punch adapted to enter between said dies to force the work therebetween and automatic means including a rotating member for moving the dies into engagement to compress said work.

13. Apparatus for making wire-core hair-pins, comprising a pair of relatively movable forming-dies, adapted to support a strip of sheet material over the gap between them when in open position, in combination with a forming-punch and means for moving the same into said gap to bend the strip into V shape to receive the core, and automatic means including a rotating member for closing said forming-dies upon the bent strip.

14. Apparatus for making wire-core hair-pins comprising a pair of relatively movable forming-dies and a gage for holding a strip of covering material over the gap between said dies, in combination with a forming-punch adapted to co-operate with said dies to crease the strip longitudinally, and automatic means including a rotating member for closing said forming-dies upon said creased strip.

15. In hair-pin machines, a rotating drum, co-operating forming-jaws carried by the drum, automatic means to feed plastic material and a core to said forming-jaws, and means to close said jaws to cause said material to inclose said core.

In testimony whereof I affix my signature, in the presence of two witnesses, this 2d day of August, 1905.

WILLIAM POPPENDIECK.
